UNITED STATES PATENT OFFICE.

WILLIAM MCINTYRE AND DELBERT L. NICHOLS, OF HARTFORD, CONNECTICUT.

DESIGN FOR A LINK FOR WIRE MATTRESSES.

SPECIFICATION forming part of Design No. 33,030, dated July 31, 1900.

Application filed June 21, 1900. Serial No. 21,114. Term of patent 7 years.

To all whom it may concern:

Be it known that we, WILLIAM MCINTYRE, a subject of the Queen of Great Britain, and DELBERT L. NICHOLS, a citizen of the United States, residing at Hartford, in the county of Hartford and State of Connecticut, have invented and produced a new and original Design for Links for Wire Mattresses, of which the following is a specification.

- 10 This invention relates to a design for links or loops especially adapted for use with wire mattresses, the leading feature of the design being a representation of a link substantially as hereinafter described.
- 15 In the drawings accompanying and forming part of this specification, Figure 1 represents a plan view of this link. Fig. 2 represents a side or edge view thereof.

Similar characters of reference designate corresponding parts in both figures of the drawings.

Referring to the accompanying drawings, the link is substantially oblong in shape and comprises a plurality of faces 3 and angles 4, forming an octagonal link or loop having a 25 pair of free ends 5, each end having a loop or eye 6.

What we claim is—

The design for a link for wire mattresses, substantially as shown and described.

WILLIAM MCINTYRE.
DELBERT L. NICHOLS.
